UNITED STATES PATENT OFFICE.

MALCOLM J. MCFARLANE, OF NEW ORLEANS, LOUISIANA.

FIRELESS COOKER AND HEATER.

Application filed March 8, 1921. Serial No. 450,777.

To all whom it may concern:

Be it known that I, MALCOLM J. MCFARLANE, citizen of the United States, residing at New Orleans, in the State of Louisiana, 5 have invented certain new and useful Improvements in Fireless Cookers and Heaters, of which the following is a specification.

The present invention relates to a new and improved electrical cooker that is convertible either as a cooker or radiator such 10 as occasion may require.

The main object of the invention is to provide a convertible device of the above character that is efficient in operation, compact and durable and which may be manufactured at a reasonable cost.

Aside from being used as a cooker proper, that is for broiling, frying, etc., the device may be used and is especially designed as a 20 fireless cooker, the initial heat being furnished through the instrumentality of a coil of electrical resistance wire.

Various other objects and advantages of my invention will become apparent during 25 the continuance of the following description.

In the drawing:

Figure 1 is a view in front elevation showing my invention as in its preferred embodiment.

30 Figure 2 is a view in vertical central section of the device taken on line 2—2 of Figure 1.

Figure 3 is a view in horizontal cross section taken on line 3—3 of Figure 1.

35 My invention consists generally of a body or housing portion 10 of suitable shape and dimensions that is preferably constructed of metal. In its front face the body portion 10 is provided with a door opening 11 and 40 about this opening is arranged an inwardly projecting flange 12. A door 13 is swung upon hinges 14 which are in turn mounted on the body 10 and is adapted to close the opening 11, the door consisting generally of

45 a metallic body 15 having inwardly projecting flanges 16 along its vertical and horizontal edges, as clearly shown in Figure 2. In order to maintain the door in a secure position when closed I provide the same with 50 pivoted handles 17 which are designed to be engaged with lugs 18 of the body portion

10. While this particular form of securing means is herein illustrated it is pointed out that I do not wish to limit myself in that respect and, therefore, that other types of 55 means may be substituted if so desired.

Within the bottom of the body 10 and below the lower edge of the opening 11 I provide a comparatively thick disc 19 of insulating material of any desired form. In 60 the upper face of this disc is cut a tortuous channel or way 20 for the reception of a coiled resistance wire 21. The disc is also provided with an opening 22 which communicates with the channel or way 20 and a 65 plug socket 23 of the body portion 10. Therefore the ends of the wire 21 are passed through the opening 22 and fasten to the socket 24 that has connection with a suitable source of electrical power by means of the 70 wire 25. While I do not wish to limit myself to the specific material used in the construction of the disc 19 it is pointed out for sake of illustration that soapstone may be used.

75 The inner wall of the body portion 10 and the door 13 is lined with a heavy coating of insulating material in order to confine the heat within the body portion. The insulating material which covers the inside of the 80 body portion 10 including the top thereof is designated by the numeral 26 while the insulating material of the door is designated by the numeral 27.

In order to allow for the escape of steam 85 from the interior of the body portion I provide a suitable air vent 28 in the top of the body portion 10 such as shown in Figure 2.

When the device is used as a fireless cooker the door 13 is of course closed but when used 90 as a radiator or heater the door is opened so that the heat from the interior will radiate into the room or other place in which the device is situated.

What is claimed is:

95 A fireless cooker and heater comprising a housing closed at its top and bottom but having an opening in the side, the said top and side walls of the housing having a facing of insulating material, an insulating disc 100 covering the inside bottom of the housing and having its upper face provided with a

tortuous channel presenting exposed arcs concentric with the center of the said disc, a coiled resistance wire disposed in said channel and having its opposite ends passing 5 exteriorly of the said housing, and a plug socket carried by an exterior portion of the said housing.

In testimony whereof I affix my signature in presence of two witnesses.

MALCOLM J. McFARLANE.

Witnesses:
